UNITED STATES PATENT OFFICE.

RALPH STUART, OF BUFFALO, NEW YORK, ASSIGNOR TO STRAUS COMPANY, OF RICHMOND, VIRGINIA, A FIRM COMPOSED OF CHARLES E. STRAUS, JR., AND ALLYN C. STRAUS.

DESIGN FOR A BORDER STRIP FOR A DISH OR SIMILAR ARTICLE.

Application filed July 24, 1928. Serial No. 27,569. Term of patent 14 years.

To all whom it may concern:

Be it known that I, RALPH STUART, a citizen of the United States of America, and a resident of Buffalo, in the county of Erie and State of New York, have invented a new, original, and ornamental Design for a Border Strip for a Dish or Similar Article, of which the following is a specification, reference being made to the accompanying drawing, forming part thereof.

Fig. 1 is a plan view of a border strip showing my new design.

Fig. 2 is an edge view of the border strip.
I claim:

The ornamental design for a border strip for a dish or similar article as shown.

RALPH STUART.
